UNITED STATES PATENT OFFICE.

ARTHUR B. WARING, OF YONKERS, NEW YORK.

HAT-BLOCKING MACHINE.

No. 881,508.

Specification of Letters Patent.

Patented March 10, 1908.

Application filed September 24, 1904. Serial No. 225,768.

To all whom it may concern:

Be it known that I, ARTHUR B. WARING, a citizen of the United States of America, and a resident of Yonkers, county of Westchester, and State of New York, have invented certain new and useful Improvements in Hat-Blocking Machines, of which the following is a specification.

One feature of the invention relates to the provision of a gage, preferably as a permanent fixture of the machine, by which the operator with a minimum of effort can ascertain the depth of crown for which the machine is adjusted.

Another feature of this invention relates to the provision of a guard and means for moving the guard in front of the open space between the brim-clamps as the brim-clamps are about to close and prior to the closure of the brim-clamps, in order, if the operator's arm should be between the clamps, that he should be warned in time to withdraw it before it is caught and crushed by the more powerfully actuated brim-clamps.

These several features have been devised and are particularly adapted for use in conjunction with hat-blocking machines such as are set forth in United States Letters Patent No. 724,404, granted to me March 31, 1903, and are herein illustrated in conjunction with the hat-blocking machine of that patent to which reference is made for such details of construction as are not herein fully illustrated and described.

Referring now to the accompanying sheet of drawings, which forms a part of this application, Figure 1 is a side elevation of a hat-blocking machine embodying the several features of my invention, viewed from the right of the machine, some of the actuating mechanism being broken away. Fig. 2 is a front view of the upper portion of the machine.

The several parts of the machine are supported in a main frame 1. A steam chest 2 to which a templet 3 with a clamping face of convex curvature from front to rear is attached, is fixed in the upper part of the machine. The steam chest and templet constitute the lower brim-clamp. An upper brim-clamp cooperates with the lower brim-clamp and consists of a steam-chest 4 and templet 5 with a clamping-face of concave curvature from front to rear which mates with the clamping-face of the lower brim-clamp. Thumb-screws 6 are used to attach the

templets to the steam-chests so that the templets may be conveniently removed and changed. The steam-chests are provided with central openings and the templets are provided with similar openings to permit the passage therethrough of a hat-block 7 for blocking the hat crown concurrently with the blocking of the brim. The upper brim-clamp is supported by two vertically sliding rods 8 which are guided in bearings at the sides of the frame, and the hat-block is supported by a central vertical rod 9 which is also guided in bearings in the frame of the machine. These rods are automatically actuated by suitable power-driven mechanism comprising a belt-driven pulley 10 on a main shaft 11 and auxiliary shafts 12 and 13 which are geared therewith. On the ends of the latter shaft are tappets 14 which engage levers 15, the levers being connected through links 16 with the vertically sliding side rods, and actuate the upper brim-clamp. The tappets engage the under sides of the levers to lift the brim-clamp. Stirrups 17 with flat bearing places are engaged by the tappets to insure sufficient clamping pressure when the upper brim-clamp is in engagement with the lower brim-clamp and interposed hat-brim.

A hand-wheel 18 turns on the upper end of the central vertical rod which supports the hat-block. A nut 19 carried by the hand-wheel engages a screw 20 which is attached to the hat-block. The hand-wheel serves to adjust the height of the hat-block with respect to the vertical rod by which it is automatically operated through the brim-clamps. The actuation of the rod and hat-block is by a tappet 21 which engages a lever 22 the forward end of which is connected to the rod through links 23 and the hat-block by reason of its attachment to the rod is positively inserted and withdrawn from the hat by the machine before the brim-clamps are parted so that the curve given by the brim-clamps will not be disturbed. The range of travel of the central rod is fixed by the proportions of the parts, but the distance through the brim-clamps to which the hat-block is lifted, is adjustable by means of the hand-wheel, and the height above the meeting faces of the brim-clamps to which the top of the hat-block is lifted will be the height of the crown that will be blocked by the machine. In order that the operator may readily inform himself as to this adjustment, a gage consisting of a slide

24 attached through a bracket 25 conveniently to the upper brim-clamp and a light 5 slideable member 26, preferably of wood, is so mounted that the lower end of the slideable member can be engaged and set by the top of the hat-block when the hat-block is at the upper end of its movement and the upper brim-clamp is engaging the lower brim-clamp, these being at the same time, by reason of a proper setting of the tappets. One 10 of the members of the gage, and preferably the slideable member, is provided with a scale of inches, and the slide is provided with a marker or line 27 against which is read the distance to which the top of the hat-block is 15 lifted above the clamping faces of the brim-clamps, and hence the height of crown that will be blocked by the machine. The gage is so adjusted that when the zero point of the 20 scale is set at the marker the lower end will be even with the clamping face of the brim-clamp to which the gage is attached. There is sufficient friction between the slide and the slideable member to hold the latter against 25 displacement by its own weight in any position in which it may be placed. To ascertain the setting of the hat-block, the operator lowers the slideable member sufficiently to be engaged by the block when at its highest 30 point of movement, and when the hat-block rises on the next revolution of the machine the gage will be automatically set and left with the indication at the height of crown for which the machine is adjusted.

35 A guard 28 in the form of a bail extends across the front of the machine, and the sides of the bail are pivoted about midway to the vertically sliding side rods which operate the upper brim-clamp. The ends of the bail are 40 hinged to the upper ends of links 29, the lower ends of which are hinged to the frame of the machine. When the upper brim-clamp descends, the front of the bail passes in front of the space between the brim-clamps 45 at about double the speed of the brim-clamp, and hence will warn the operator by striking his arm if it should be in the way, in advance

of the closing of the brim-clamps, so that he can withdraw his arm before it is caught too firmly for removal. The bail is of light material and clears the front of the machine so that it will not of itself catch the arm so tightly that it cannot be pulled out. 50

What I claim as new and desire to secure by Letters Patent of the United States is: 55

1. In a hat-blocking machine, the combination of two brim-clamps with curved surfaces one of which is convex and the other concave, means for closing the same, a hat-block, means on which the hat-block is adjustably supported for moving the hat-block through the brim-clamps, and a gage comprising a slide supported by one of the brim-clamps and a slideable member supported by the slide in the path of the hat-block, substantially as described. 60

2. In a hat-blocking machine, the combination of brim-clamps, means for closing the same, a hat-block, means on which the hat-block is adjustably supported for moving the hat-block through the brim clamps, and a gage comprising a slide supported by one of the brim-clamps and a slideable member supported by the slide in the path of the hat-block, one of the members of the gage being provided with a scale and the other member with a marker for the scale, substantially as described. 70

3. In a hat-blocking machine, the combination of brim-clamps, one movable toward the other, a guard, and means for automatically moving the movable brim-clamp away from and returning it to the other brim-clamp and passing the guard in front of the space between the brim-clamps in advance of the closure of the brim-clamps, substantially as described. 80

Signed by me at Yonkers, N. Y., this 20th day of Sept. 1904.

ARTHUR B. WARING.
